IRON VANE ELECTRICAL INSTRUMENT

Alfred J. Huber, Elizabeth, N. J.

Application February 11, 1954, Serial No. 409,700

6 Claims. (Cl. 200—103)

This invention relates to electrical instruments and more particularly to an iron vane repulsion type instrument of improved construction affording certain manufacturing and operating advantages.

Instruments of the type contemplated by this invention respond to current flowing in the field coil. Such current flow induces like magnetic poles in a fixed iron vane and an associated movable iron vane whereby the resulting repulsion effect imparts a rotary movement to the movable vane in correspondence with the magnitude of the current flow. One problem associated with instruments of this class has been to increase the sensitivity of the instrument without an attendant increase in the overall size of the instrument and the complexity of construction.

An object of this invention is the provision of an iron vane type of instrument of small size, simple construction and rugged character and which instrument will possess a high response sensitivity.

An object of this invention is the provision of an iron vane type of instrument comprising a field coil supported on a hollow, flanged spool, a plurality of axially-disposed iron vanes secured in fixed position within the spool and extending radially toward the spool axis, and a plurality of pivotally-mounted movable iron vanes operatively associated with the fixed vanes, said movable vanes being rotatable about the spool axis.

An object of this invention is the provision of an iron vane type of instrument comprising a hollow insulator spool having an upper and lower flange, a field coil carried by the spool, a plurality of axially-disposed iron vanes secured to the inner wall of the spool, said vanes extending toward the spool axis, a corresponding plurality of movable iron vanes symmetrically disposed about the spool axis and individually co-acting with the fixed vanes when the field coil is energized, aligned pivot posts carried by the movable vanes, pivot pins extending outwardly of the pivot posts, a bearing carried by the lower spool flange and supporting one pivot pin, a second bearing carried by a bridge supported by the upper spool flange and cooperating with the other pivot pin, spring means normally biasing the movable vanes in a given direction, and a movable arm secured to one of said pivot posts.

An object of this invention is the provision of a movable vane structure for a repulsion type instrument and comprising a pair of thin, substantially-rectangular iron plates, each plate being provided with a rectangular notch at each end and an axial slot extending from one such notch to the center of the plate, said plates being of bilaterally-symmetrical form taken with respect to the longitudinal axis and the formation of the identical plate being such that when one plate is reversed relative to the other the plates can be assembled to form a structure having a cross shape in transverse section.

These and other objects and advantages will become apparent from the following description when taken with the accompanying drawings illustrating a particular embodiment of the invention. It will be understood that

2

the drawings are for purposes of description and are not to be construed as defining the scope or limits of the invention, reference being had for the latter purpose to the appended claims.

5 In the drawings wherein like reference characters denote like parts in the several views:

Figure 1 is a side view of an instrument made in accordance with this invention;

10 Figure 2 is a top view of such instrument;

Figure 3 is a transverse section taken along the line A—A of Figure 1;

Figure 4 is an enlarged elevation view showing the construction of the two rectangular plates which made up the movable system;

Figure 5 is an isometric, exploded view showing the cross-shaped movable vanes, the upper and lower pivot posts, and the pivot pins which form the axis about which the movable system rotates;

Figure 6 is an elevation showing the assembled movable system;

Figure 7 is an enlarged fragmentary view showing the assembly of the movable arm and biasing spring on the upper pivot post;

25 Figure 8 is a similar view showing the assembly of the upper bridge;

Figure 9 is a transverse section taken along the line B—B of Figure 1 but with the movable vanes removed;

Figure 10 is similar to Figure 3 and showing the addition of cover plates which serve as dust covers and as 30 a closure for the spool to thereby increase the damping factor of the instrument.

Reference is now made to Figures 1 and 2. The field coil 10 is wound on an insulator spool having a bottom flange 11 and a top flange 12. A lower jewel screw 13 is threaded into a central hole provided in the flange 11 and is locked in relatively fixed position by a nut 14. An upper jewel screw 15 is similarly carried by a bridge 16 that is secured to the diametrically-opposite posts 17 by the screws 18, said posts having lower ends threaded 40 into suitable holes provided in the upper flange 12. Alternatively, these posts may be molded as integral parts of the spool. A nut 19 serves to lock the jewel screw in fixed position. The movable system of the instrument is pivotally supported by the jewel screws 13, 15 as will be described in more detail hereinbelow. For the moment attention is directed to the fact that the upper part of the instrument movable system includes a pivot post 20 which carries a pivot pin for cooperation with the upper jewel screw 15 and which post is arranged to carry the spiral spring 21 and the movable arm 22. Those skilled in this art will understand that in the case of an indicating instrument the movable arm 22 may be a pointer adapted to cooperate with a suitably calibrated scale. However, the illustrated instrument is a relay and the movable arm 22 carries a small bushing 24 made of a material having good electrical qualities such as silver, platinum-iridium, etc. Upon rotary movement of the movable system, the contact 24 will engage a cooperating, similar contact 25 which lies in the arcuate path of travel of the movable contact and is secured to an abutment supported on the bridge 16, as will be described more specifically hereinbelow with reference to Figure 8.

65 The relative arrangement of the fixed and movable iron vanes is illustrated in Figure 3 which is a transverse sectional view taken along the line A—A of Figure 1. Here are shown the top spool flange 12 and the bridge-supporting posts 17. The fixed magnetic system of the instrument includes four vanes 30, 31, 32, 33 which are made of thin iron sheet and which extend axially of the spool. These vanes are spaced apart 90 angular degrees and each is secured in fixed position by having one long side thereof cemented within longitudinal slots

formed in the inner wall of the tubular section of the spool. Alternatively, these vanes may be directly molded in position when the spool is made by a molding operation. A better understanding of this arrangement will be had by reference to Figure 9 which is a cross-sectional view taken along the line B—B of Figure 1 and which view shows the wall 34 of the tubular portion of the spool. Referring again to Figure 3, the movable system of the instrument comprises four, thin iron vanes 35, 36, 37, 38, which are pivotally mounted for rotation about the longitudinal axis of the spool. Those skilled in this art will understand that when a current flows in the field coil the resulting magnetic lines of force will magnetize the iron vanes so as to provide similar magnetic poles on the fixed and movable vanes. Consequently, there is developed a repulsion force tending to separate the movable vanes from the fixed vanes. Since the movable vanes are arranged for rotation about the spool axis such repulsion force results in an angular movement of the movable vanes.

Reference is now made to Figure 4 which is an elevation view showing the two, thin, soft-iron plates which, when assembled, form the four movable vanes of the instrument. Each of the plates 40, 49' are of identical configuration, having longitudinally-aligned, substantially rectangular notches 42, 43, and 42', 43' formed at opposite ends. Further, each plate includes a longitudinal slot 44, 44', extending from the respective notches 42, 42' to the center of the plate. These slots have a width substantially equal to the thickness of the plate whereby when the plates are reversely disposed, as shown in Figure 4, they may be assembled to form a cross-like structure 45, as shown in Figure 5. It is apparent that the associated end surfaces of each plate will be in a common plane when the longitudinal slots extend at least to the center of the plates. The assembled plates are preferably set in an appropriate fixture to assure a mutually perpendicular orientation of the four vanes 34, 35, 36 and 37. Even though the longitudinal slots have a width such that the two plates must be force-fitted together, it is desirable to apply suitable cement along the mutually-contacting edges of the plates to provide a rugged assembled unit. Attention is here directed to the fact that the notches formed in the edges of the plates form, effectively, receptacles 47, 48, for the circular pivot posts 20, 20' the effective diameters of such receptacles corresponding to the outer diameters of the pivot posts. While the vane structure 45 is retained in a suitable fixture the pivot posts are assembled and cemented thereto as shown in Figure 6. Each of the pivot posts includes an axial bore into which are driven the associated, pointed pivots 49, 50, said pivots being precisely aligned to form the axis of rotation of the movable system. It is well to here point out that the upper pivot post 20 is somewhat longer than the lower post 20' since the upper portion of the instrument carries the movable arm and the spiral biasing spring thereby requiring a spacing of the upper jewel screw from the upper spool flange, as is apparent from a study of Figure 1. Also, the upper pivot post 20 is provided with a reduced-diameter outer end 51 for purposes now to be described.

Figure 7 is a fragmentary elevation, with parts in section, showing the upper portion of the movable system. In this view are shown the vanes 35, 37 and 38, the upper pivot post 20 carrying the upper pivot 49, the spiral spring 21 having its inner end soldered to an abutment 53 and the cross arm 22 carrying the contact 24 at one end. As explained with reference to Figure 5, the pivot post 20 includes a reduced diameter outer end 51 providing a shoulder to support the cross arm 22 and the spring abutment 53. It may here be pointed out that the cross arm 22 includes a central hub provided with a hole and that the tail and side arms carry adjustable balance weights 54, see also Figure 1, for dynamically balancing

the entire movable system, all in accordance with conventional practice in this art. The cross arm and the abutment 53 are secured in fixed position on the pivot post 22 by peening over the end of the post, as shown.

Reference is now made to Figure 8 which illustrates those parts which are operatively associated with the movable system components shown in Figure 7. Here are shown the bridge 16 supported by and secured to the posts 17 by the screws 18. The upper jewel screw 15 extends through a threaded, central hole in the bridge and has a length sufficient to extend upwardly beyond a stacked arrangement of parts necessary for the proper functioning of the instrument. The spring abutment 56 includes an upwardly directed outer end and a downwardly directed inner end to which the outer end of the spiral spring 21 is soldered, see Figure 7. A study of Figures 7 and 8 will show that the movable contact 24 is in electrical contact with the bridge 16 through the movable arm 22, spring abutment 53, spring 21 and abutment 56. Thus, current can be directed to such movable contact by connecting a wire to either of the bridge-fastening screws 18. Alternatively, a flexible lead wire may be soldered to the outer end of the abutment 56. Disposed over the abutment 56 is an insulator bushing 57 having a shank to accept the reversely-bent crank 58 and the entire stack is secured in relatively fixed position by means of the nut 19 and the spring washer 59. The nut 19 is threaded upon the jewel screw to the extent required to frictionally retain the abutment 56 and the crank 58 in any preset angular position during normal operations of the instrument. The inner, downwardly bent end of the crank has secured thereto, as by solder, the stationary relay contact 25 (see also Figures 1 and 2) and it should be apparent that the position of the contact 25 relative to the movable contact 24 can be adjusted upon rotation of the crank 58. Likewise, it is clear from Figure 8 that the crank and the contact 25, are electrically isolated from the entire movable system by the insulator bushing 57 and the insulator washer 60. Consequently, an external circuit connected between the bridge 16 and the crank 58 will be completed upon closure of the relay contacts 24, 25. The point of closure of the relay contacts can be adjusted by rotation of the crank to set the relatively stationary contact 25 at a desired angular position relative to the zero position of the instrument movable system. Further, the zero position, and the sensitivity of the instrument can be adjusted by rotation of the abutment 56 which controls the angular orientation of the biasing spring 21.

It is pointed out that the movable vanes of the instrument are disposed entirely within the tubular portion of the spool carrying the field coil. This feature facilitates the provision of a closed chamber to serve as a means for damping the rotation of the movable system. Figure 10 is similar to Figure 3 and shows the addition of two, similar flat plates 63, 64 of generally semi-circular configuration. Each of the plates is pivotally attached to one of the bridge-supporting posts 17. When the plates are moved to the closed position, as is the plate 63, there is formed a substantially circular plate which closes the upper opening of the spool except for the central aperture formed by reason of the step-like complementary plate edges, which aperture clears the upper pivot post 20. By so confining the air within the spool chamber, I provide a practical degree of air damping for the instrument and, at the same time, protect the interior of the instrument against the entrance of foreign matter which may interfere with instrument operation.

The above-described instrument may be housed in a suitable case as, for example, a hermetically sealed can provided with conventional solder-sealed or pin-type terminals to which the ends of the field coil and the relay contacts are connected.

Having now described my invention in detail in accordance with the requirements of the patent statutes,

those skilled in this art will find no difficulty in making changes and modifications in the illustrated instrument construction to meet specific requirements. Such changes and modifications may be made without departing from the scope and spirit of the invention as set forth in the following claims.

I claim:

1. An electrical instrument comprising an insulator spool having an upper and a lower flange joined by a hollow tube; a field coil encircling the tube; a fixed iron vane system including four substantially-rectangular, soft-iron vanes longitudinally disposed within the tube and extending substantially the full axial extent of the field coil, each vane extending inwardly of the tube and having a long side disposed within a longitudinal groove formed in the inner wall of the tube; a movable system comprising two flat sheets of soft iron secured together so as to form four substantially-rectangular, soft-iron vanes disposed in mutually perpendicular planes, said vanes having an axial length substantially equal to that of the fixed vanes; alined pivot posts secured at opposite ends of the movable system vanes, each post carrying a pivot; a bearing carried by the lower spool flange and cooperating with one of the pivots; a bearing carried by a bridge member supported by the upper spool flange and cooperating with the other pivot; and spring means secured to the movable system and normally biasing same in a direction to bring the movable vanes proximate to the fixed vanes.

2. The invention as recited in claim 1 wherein the movable system vanes are provided with end notches which are symmetrical with respect to the axis formed by the pivot pins, and the pivot posts are partially disposed within such notches.

3. The invention as recited in claim 1, in combination with a pair of flat plates each pivotally attached to posts supporting the bridge member from the upper spool flange, said plates being pivotally slidale along the outer

surfaces of the upper spool flange to form a closure for the said tube.

4. The invention as recited in claim 1, including a movable contact member secured to the movable system and a cooperating contact member pivotally supported on said bridge member, said cooperating member extending into the arcuate path of travel of said movable contact member; and means electrically isolating the cooperating contact member from the bridge member.

5. A movable iron vane system for an electrical instrument comprising a pair of thin, rectangular, soft-iron plates, each plate having a substantially-rectangular central notch formed in each end and including a central, longitudinal slot extending from one such notch to at least the center of the plate, said plates being reversely disposed relative to each other and in perpendicular planes so that the ends thereof are co-planar, a circular pivot post seated in the cooperating notches at the plate ends and secured to the side walls defining such cooperating plate notches, and alined pivot pins extending from said pivot posts.

6. The invention as recited in claim 5, wherein one of said pivot posts includes a reduced-diameter outer portion, a movable arm having a hub section provided with a hole and disposed over said outer portion of the pivot post; and a spring abutment having a hole and disposed over the outer portion of the pivot post, the free end of said outer post portion being upset to secure the movable arm and abutment to the pivot post.
